ATTORNEYS

UNITED STATES PATENT OFFICE.

JOHN H. KILLION, OF CHICAGO, ILLINOIS.

KNOCKDOWN CONTAINER.

Application filed October 16, 1920. Serial No. 417,408.

To all whom it may concern:

Be it known that I, JOHN H. KILLION, a citizen of the United States, and a resident of Chicago, in the county of Cook and State 5 of Illinois, have invented a new and useful Improvement in Knockdown Containers, of which the following is a full, clear, and exact description.

My invention relates to improvements in 10 knock down containers, and it consists in the combinations, constructions, and arrangements herein described and claimed.

An object of my invention is to provide a knock-down container comprising relatively 15 few parts which are inter-engaged to maintain the container in set-up or assembled condition.

A further object of my invention is to provide a device of the type described that 20 is simple in construction and operation, not likely to get out of order easily, and thoroughly practical commercially.

A further object of my invention is to provide a device of the type described that 25 can be disassembled and the parts thereof packed to occupy a comparatively small space, wherefore the containers when empty may be readily conveyed from place to place and used repeatedly.

30 A further object of my invention is to provide a device of the type described that is light in weight, strong and durable, and capable of being produced in large quantities quickly and cheaply.

35 Other objects and advantages will appear in the following specification, and the novel features of the invention will be particularly pointed out in the appended claims.

My invention is illustrated in the accompanying drawings, forming part of this application in which

Figure 1 is a side elevation, partly broken away and in section, of an embodiment of my invention,

45 Figure 2 is a plan view of a portion of the form of the device shown in Figure 1,

Figures 3 and 4 are side elevations, partly broken away and in section, of modified forms of the same device,

50 Figure 5 is a similar view of another modification of the form of the device illustrated in Fig. 1,

Figures 6 and 7 are plan views of modified forms of the portion of the device shown 55 in Fig. 2,

Figure 8 is a side elevation, partly broken away and in section of still another modified form of the device,

Figure 9 is a detail view of a developed fragmentary portion of the form of the device shown in Fig. 8.

Reference is to be had to the drawings in which like reference numerals denote like parts throughout the several views.

In Figure 1, a substantially cylindrical 65 body portion is denoted by 1. This body portion in its developed form comprises a single plate which is preferably formed of metal, but may be made of any suitable material, such as fiber, or the like. The upper 70 and lower ends of the body portion 1 are each bent outwardly at 3—3 and then downwardly and upwardly, respectively, thus providing the overlying stiffening member 2—2. A retaining member 4 that is bent 75 into U-shape is secured at 5, as by welding, to the body portion along one side edge thereof and is adapted to receive the other side edge of the body portion when the latter is bent into cylindrical form, as shown. The 80 inherent resiliency of the material comprising the body portion will tend to maintain the same in the position shown in Figure 2.

A plurality of spaced apart openings 6 are provided in the body portion 1 at its 85 rim edge. Straps 7 each have one end inserted through one of the openings 6 and bent downwardly along the inner wall of the body portion. The body portion 1 is further held in cylindrical form by the engagement of heads or cover portions therewith. Each of the latter comprises a depressed central portion 8 and a substantially U-shaped 90 marginal portion 9 adapted to receive a rim edge of the body portion 1 and to have its outer wall 14 overlapping a portion of the body portion 1 adjacent the end. The straps 7 are then bent around the lower edges of one of the overlying stiffeners 2 and the outer wall 14 of the head or cover and upwardly at 10, then inwardly at 11, downwardly at 12 into contact with the depressed central portion 8, and then inwardly at 13 to overlap the central portion 8, as best seen in Figure 1.

100 From the foregoing description of the various parts of the device, the operation thereof may be readily understood. It will be seen that the provision of the overlying stiffeners 2—2 and the arrangement of the heads or covers relative the body portion 1 105

110

strengthens the container at the points at which stress is likely to be applied in service. Furthermore, the cover portions or heads are maintained in the positions shown by the engagement of the same with the cylindrical body portion and by the straps 7, while also serving to maintain the straps 7 in operative position. That is, the parts of the device not only serve their obvious functions, but also co-act to maintain the container in assembled or set-up condition, wherefore the device is very strong and durable and not likely to be impaired when subjected to the shocks and jars incident to its service.

15 One of the heads or cover portions may be secured in position and the container then filled. The other head or cover is then secured in position and the device is ready for shipment. When not in use, the device may be disassembled and the parts thereof packed to occupy but a small space and secured in packages which may be stored away or readily transported from place to place at a relatively low cost. The fastening straps 7 may be discarded when the container is emptied, since their construction is such that they may be replaced readily at a low cost.

Referring now to Figure 3, I show a somewhat different means in the same device for maintaining the heads or cover portions in position. In this form of the device, a body portion 19 is not provided with a overhanging portion 2 at its ends, but is otherwise similar to the body portion 1. Diametrically opposed openings 20 are provided in the body portion adjacent the ends thereof. Straps 21, which extend entirely across the bore of the container preferably at right angles to each other, have their ends projecting through the openings 20. Cover portions or heads such as have been described are placed in position on the body portion 19 and the projecting portions of the straps 21 are bent upwardly, or downwardly, as the case may be, at 22, inwardly at 23, and upwardly or downwardly at 24 around the U-shaped marginal portion 9 of the head and into engagement with the depressed central portion thereof. The straps are finally bent inwardly at 25 adjacent their ends to overlap the depressed central portion 8. The cover portions are therefore securely held in position.

Referring now to Figure 4 in which another embodiment of the same invention is illustrated, it will be noted that I provide a cylindrical body portion 30 that is similar to the body portion 19. I make use of the fastening straps 21 which project through diametrically opposed openings 31 in the walls of the body portion 30 adjacent the ends thereof and are bent around the edges of the body portion 30, as described, into engagement with heads 32 which in this form 65 of the device consists of circular disks whose

outer edges contact with the inner walls of the body portion 30 adjacent the ends thereof.

Referring now to Figure 5, there is illustrated therein a form of the device having a body portion 40 that is identical in essential respects with the body portion 19. Cover portions or heads, such as described, are provided and maintained in position relative to the body portion 40 in the manner described. It is desirable that containers embodying my invention and intended to be used for certain purposes should be provided with a bail or handle to permit the same to be readily carried from place to place. I therefore provide detachable means for securing the handle to the container when desired, such means comprising straps each bent at 41 or intermediate its length, one portion thereof being bent at 42 and 43 around the edge of the marginal portion 14 of the cover and then at 44 around the edge of the body portion. The other portion of the strap is bent at 46 and 47 around the U-shaped portion 9 of the cover or head and into engagement with the depressed central portion 8 thereof. It will be understood that two of these straps or bars are provided and that the same are secured to the container in the manner described at diametrically opposite points. The ends of a bail or handle 48 are secured at 49 to the outstanding lug portions of these straps.

Referring now to Figures 6 and 7, I show two modified forms of the body portion 1. In the form shown in Figure 6, the body portion is formed of four arcuate similar sections 50, 51, 52, and 53. The side edges of the section 50 are bent outwardly and then toward each other at 50^a—50^b to form fins or tongues 50^b—50^a. In a like manner, the sections 51, 52, and 53 have their sides bent at 51^a—51^b, 52^a—52^b, and 53^a—53^b to form fins or tongues 51^b—51^a, 52^b—52^a, and 53^b—53^a, respectively. Reinforcing clips 54, each provided with opposed grooves or pockets 55 and 56 adapted to receive the tongues formed integrally with adjacent portions of the several sections maintain the sections assembled to form the substantially cylindrical body portion illustrated, which is also strengthened by the provision of the reinforcing clips 54. In Figure 7, the form of the body portion illustrated comprises a single plate 60 having its opposite sides bent adjacent the edges thereof at 61^a and 61^b to provide the fins 61 and 62, respectively. A fastening clip 63 having opposed grooves or pockets 64 and 65 is adapted to receive the fins 61 and 62 and to hold the side edges of the plate 60 in the position shown, thereby providing a cylindrical body portion which may be fitted with any one of the several heads or cover portions described.

Referring now to Figures 8 and 9, a body

portion 70 is made up of sections which are identical in essential respects with those shown in Figure 6 and consequently require no further description. A fragmentary portion 5 of a developed reenforcing and fastening clip such as is employed to maintain the several sections of the body portion 70 in operative position is shown in detail in Figure 9.

10 It will be noted that the clip has flaps 71 which are bent back upon the portion 73, the flaps being bent along the lines 72. The dotted lines in Figure 9 indicate the flaps 71. A portion of the body 73 extends beyond the ends of the flaps 71 and is divided into three segments 74, 75, and 76. The segments 75 and 76 are bent over the ends of the container 70, thus preventing longitudinal movement of the clip with respect to the 20 container. The flaps 71 form pockets which receive the portions of the sections in the container 70, in the same manner as the portions 61 and 62 are received in the grooves 64 and 65 (see Figure 7). The covers 8 25 may now be disposed over the completed container 70 and are held in place by the segments 74 which are bent thereover in the manner illustrated in Figure 8.

The device may be used in the same manner as an ordinary container, since it may be readily separated into its parts and has the advantage of being readily transportable at a low cost when disassembled.

I claim:

35 1. A knock-down container comprising a

cylindrical body portion formed of a normally flat rectangular plate having one edge adapted to engage with the opposite edge thereof when the plate is bent into cylindrical form, said body portion being formed 40 with pairs of diametrically opposed openings lying in the same plane adjacent each end of the container, diametrically disposed straps having their ends projected through said opposite openings, and a closure for 45 each end of said body portion, each closure having a depressed central portion and a marginal portion provided with a groove adapted to receive a rim edge of said body portion, the projecting ends of said fastening members being bent over the marginal portions of said closures to overlie the central portions thereof.

2. A knock-down container comprising a cylindrical body portion made from a single plate, the ends of said cylinder being bent back upon themselves, diametrically opposed openings in the ends of said body portion, straps disposed between the bent back portions and the wall of said body portion and 55 projected through said openings, the ends of said straps projecting through said openings being bent inwardly flush with the inner wall of said body portion, and covers disposed over the ends of said body portion, 60 said covers having annular grooves adapted to receive the ends of said body portion, the free ends of said straps being bent over said covers to secure said covers in place.

JOHN H. KILLION.
